UNITED STATES PATENT OFFICE.

FRED EVANS, OF NEW YORK, N. Y., ASSIGNOR TO PHILIP FLORIN, OF NEW YORK, N. Y.

COIN-PURSE.

1,193,771.

Specification of Letters Patent.

Patented Aug. 8, 1916.

Application filed December 8, 1915. Serial No. 65,651.

To all whom it may concern:

Be it known that I, FRED EVANS, residing at New York, in the county of New York and State of New York, have invented certain new and useful Improvements in Coin-Purses, of which the following is a specification.

This invention relates to a coin purse and the object thereof is to provide a simple, cheap, practical and efficient article of this class.

A further object is to provide a purse in which the coins of the several denominations may be retained within separate compartments, and to provide means whereby the coins may be readily and conveniently removed from the compartments as occasion arises.

A further object is to provide means for retaining the coins within the compartments and to retain them against undue rattling.

A further object is to provide means whereby the coins may be visible at all times even though the purse be closed, to the particular end that the person carrying the purse may ascertain whether or not a coin of a certain denomination is within the purse without necessity for opening the purse.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention: Figure 1 is a perspective view of a purse constructed in accordance with the provisions of this invention. Fig. 2 is a transverse sectional view taken upon the plane of line II—II of Fig. 1. Fig. 3 is a bottom plan view of the purse opened. Fig. 4 is a top plan view of the purse opened. Fig. 5 is a view similar to Fig. 2, but illustrating a modification.

Referring to the drawings for a detailed description of the structure illustrated therein, the reference character L indicates

the body of the purse, and H the cover or wrapper forming part of the purse.

The body is formed of a block of material, either wood, or some molded composition, such as papier-mâché, hard rubber, or the like. It is provided with a plurality of seats G therein. The bottom wall of each seat is provided with an aperture 1 which extends through the opposite surface of the body so that any coins resting in the seats may be observed from the back of the body through said apertures.

The seats G are of preferably different sizes so as to accommodate the different denominations of coins, as will be readily understood.

The formation of the apertures 1 through the bottom walls of the seats leave only enough of said bottom walls to constitute annular ridges upon which the coins rest.

The cover H is preferably of leather or other suitable material and is fixed, by glue or other means, to the under surface of the body L. Extending flaps 2 and 3 are provided and adapted to be folded about the sides of the body and over upon the top thereof. The flap 2 is preferably provided with a plurality of embossed portions 4 arranged to overlie the seats G when said flap 2 is folded over the upper surface of the body. These parts 4 serve to resiliently maintain the coins within the seats and prevent undue rattling. The flap 3 is intended to be folded over the flap 2 after said flap 2 has been folded, and said flap 3 is provided with a snap fastener 5 for engaging a co-operative portion 6 carried by the flap 2, whereby both said flaps may be locked in closed position. When the parts 5 and 6 are locked, it is practically impossible for the coins to become displaced from the seats G. That portion of the cover H which is fixed to the under surface of the body is preferably provided with apertures 7 mating the apertures 1 of the seats G. By this means the coins within the seats may be readily observed regardless of whether the flaps 2 and 3 be locked closed or not. By this means also the operator may readily displace the coins from any one or more seats, after the flaps 2 and 3 are opened, by simply inserting the end of his finger through the apertures and raising the coins slightly.

In the modification shown in Fig. 5, the

apertures 7 are omitted and in their place the portions of the cover which underlie the apertures 1 are embossed so as to provide flabby or flexible portions as 8, by means of 5 which the coins may be lifted through pressure of the end of the operator's finger upon said portions 8. In this modification, of course, the coins are not visible when the purse is closed.

10 The body L is preferably provided with ridges 9 at its opposite ends to compensate for the thickness of the cover H and to present a desirable neat appearance.

15 As many changes could be made in this construction without departing from the scope of the following claims, it is intended that all matter contained in the above description or shown in the accompanying drawing shall be interpreted as illustrative 20 only and not in a limiting sense.

Having thus described my invention what I claim as new and desire to secure by Letters Patent is:

1. A purse for containing coins or the 25 like, comprising a body member and a cover member, the cover member being fixed to the under surface of the body member, the body member and the cover member having mating apertures therethrough, the apertures 30 through the body member being adapted for receiving coins, the apertures through the body having ridges provided therein for preventing displacement of the coins through the bottom end of the apertures, 35 and the cover member having parts adapted to be folded about the body member for retaining the coins against displacement from the upper ends of the apertures.

2. A purse for containing coins or the 40 like, comprising a body member and a cover member, the body member having a seat formed through the upper surface thereof of a size to receive one or more coins laid flat in said seat, said seat being formed entirely within the marginal border of said 45 body, and there being an opening in the

bottom of said seat through which means may be introduced to force the coin or coins upwardly from said seat.

3. A purse for containing coins or the 50 like, comprising a body member and a cover member, the body member having a seat formed through the upper surface thereof of a size to receive one or more coins laid flat in said seat, said seat being formed entirely within the marginal border of said body, and said cover member being fixed to the body beneath said seat and having an opening therethrough through which means may be inserted to force the coin or coins 55 upwardly from said seat.

4. A purse for containing coins or the 60 like, comprising a body member and a cover member, the body member having an opening therein for receiving one or more coins laid flat in said opening, the cover member having a part disposed beneath the body member formed with means permitting the coin or coins within the seat to be forced upwardly from said seat, and said cover member 65 also having a part adapted to be folded over the upper surface of the body member normally to retain the coin or coins against accidental displacement from the upper end of the seat.

5. A purse for containing coins or the 70 like, comprising a body member having a seat formed through the upper surface thereof of a size to receive one or more coins laid flat therein, the seat having a 75 bottom wall therein, and the said bottom wall being formed with means permitting the coin or coins within the seat to be manually operated upon from beneath to force the coins upwardly from said seat.

85 In testimony whereof I affix my signature in the presence of two witnesses.

FRED EVANS.
